UNITED STATES PATENT OFFICE.

EDWARD J. MILLER, OF ST. LOUIS, MISSOURI, ASSIGNOR TO ST. LOUIS SCREW COMPANY, OF ST. LOUIS, MISSOURI, A CORPORATION OF MISSOURI.

METAL-HEATING APPARATUS.

Application filed December 22, 1926. Serial No. 156,305.

My invention pertains to metal heating apparatus and particularly to a method and means of maintaining a constant supply of metal heated to a sufficiently high temperature for forging and other operations, whereby an automatic bolt machine, for example, can be kept in continuous operation.

So far as I am aware the only two prior methods proposed for accomplishing this result, are to convey a rod to be heated in a straight line through the furnace, or in a helical path therein. The first requires a very long furnace, undesirable with respect both to space and efficiency; and the second is very difficult of satisfactory accomplishment for a number of reasons, among which is the varying rigidity of the material under different stages of heating.

By the means herein described I am enabled to accomplish the desired result with a relatively small furnace and at the same time avoid the difficulties and disadvantages incident to either passing the metal in uncoiled form through a long furnace, or attempting to uncoil and manipulate it while it is being heated. By my method I am also able to readily so regulate the rate of heating to the character of the material and the requirements of the particular machine to which it is to be supplied, that a constant supply of the material heated to the desired temperature will be available.

Other objects and advantages of my invention will appear from the following description.

In the accompanying drawings Figure 1 is a plan view of a furnace and associated apparatus embodying my invention; Figure 2 is a front elevation of the furnace; Figure 3 is a view partly in elevation and partly in section showing a metal holder or reel, and means for rotatively supporting the same at the material delivery point; Figure 4 is a view of the reel supporting mechanism at right angles to Figure 3; and Figure 5 is a plan view along the line 5—5' of Figure 3.

1 is the rear, and 2 and 3 the side walls of the furnace which is provided with front openings adapted to be closed by doors 4 and 5. A closed two-rail track 6 extends through the furnace chamber and has a portion outside the furnace, as shown. The material to be heated is conveyed through the furnace in coil form, preferably the ordinary commercial coils as obtained from rod

mills, being used. For supporting and conveying the coils, coil holders 7 to 7^c, which will be more particularly described herein-after, are employed, these holders being provided with means whereby they are maintained in sliding relation with the track. The wall 2 of the furnace is provided with an opening 8 for the insertion of a tool for pushing the coil holders along the rear part of the track, and the wall 3 with a material delivery opening 9.

For the purpose of readily uncoiling the heated rod and delivering it to the bolt machine located outside the furnace, mechanism is employed for elevating from the track and rotatably supporting a coil holder when it has been conveyed to the delivery position (the position of holder 7 in the furnace as shown in the drawing). This mechanism is best shown in Figures 3, 4 and 5 and comprises a vertical spindle 10 having a conical upper end 11 and rotatively supported at its lower end by bearing means 12. To non-frictionally maintain the spindle in vertical position rollers 13, 14 and 15 are employed, all of which bear on the spindle. 13 and 14 are fixedly mounted, as shown, and 15 is mounted on the end of lever 16, which is pivotally mounted at 17. This lever 16 is normally held in operative position by means of a spring, not shown, but may be actuated to withdraw roller 15 from contact with the spindle in order that the spindle may be more readily elevated to its operating position. The spindle elevating mechanism comprises the bar 18 slidably secured to the uprights 19 and 20 and by means of links 21 and 22 to cranks 23 and 24 on shaft 25. This shaft is rotated by means of crank 26 connected thereto by chain and sprocket gearing, as shown.

The coil holders or reels have a hub 27 provided with a conical recess opening downward for reception and ready engagement with the end of the spindle and have spaced arms, as shown, for supporting the coils of material to be heated. The base of the hub of the holder is adapted to rest on the rails of the track 6 and is provided with a circular projecting shoulder 28 as shown (see dotted lines on holder 7^a) extending below the surface of the rails which engages with the inner sides of the rails to maintain the holder in position thereon as it is slid along.

- I have found it desirable to curve the ends of the reel arms in the direction opposite to the direction of rotation of the reel in order to reduce the interference to rotation of the holder which would occur when the rod slipped off the end of a straight arm before the arm had passed from the line of motion of the rod to the delivery opening in the forward wall.
- 10 I have also found it desirable to provide the holder with pivoted retaining members 29 which overlie the coils and the ends of which are likewise curved in the same direction and for the same reason as the ends of the lower arms of the holder, the rod being here normally delivered from the under side of the retainers and often from contact therewith.
- 15 Referring to the operation of the apparatus described, the furnace chamber may be heated by any suitable means, not shown, and coil holders with coils of the rod material to be heated are progressively introduced therein at sufficient intervals, until the

- 20 furnace is fully charged with material, that the various coils will have been sufficiently heated by the time but not before they reach the delivery position in the furnace. The furnace having thus been established in operation and the coil at the delivery point brought to the desired temperature, the spindle 10 is elevated, thereby lifting the coil holder from the track and rotatively mounting it, whereby the rod may be unwound and pass from the furnace to the bolt machine through the opening 9 in the furnace wall. During the period of withdrawing the material from this coil the other coils in the furnace are being progressively brought to the proper temperature. When the material is delivered from the coil holder the spindle is lowered to replace the holder on track and it is brought out of the furnace through door 5; the next succeeding coil to the rear in the furnace is brought to the delivery point; and the other coils therein each moved forward, whereby the empty holder (7, for example, two positions of which are shown in the drawings) can be provided with another coil to be heated while on the outer portion of the track and inserted into the furnace through the door 4.

- It will be apparent from the foregoing that I am enabled to maintain a constant supply of heated rod for the bolt machine, the only necessary interruption in the operation of that machine being the time required to shift a coil to the delivery position from a position adjacent thereto. By regulating the temperature of the furnace and the amount of material in a given coil I can readily adjust the operation to proper conditions for different sizes of material and different rates of delivery.

Modifications in the particular apparatus

herein described can be made without departing from my invention and I therefore do not intend that its scope be limited other than by the appended claims.

Having fully described my invention, 70 what I claim as new and desire to secure by Letters Patent of the United States is:

1. In apparatus for heating material in coils, a furnace chamber having a material delivery opening, a closed track a portion of which is located outside the chamber and a portion within said chamber, a plurality of material holders mounted to move on said track, and rotatable holder supporting means positioned to be engageable with a holder when same is in a predetermined position with respect to the material delivery opening of the furnace.
2. In apparatus for heating material in coils, a furnace chamber having a material delivery opening, a closed track a portion of which is located outside the chamber and a portion within said chamber, a plurality of material holders mounted to move on said track, rotatable holder supporting means positioned to be engageable with a holder when same is in a predetermined position with respect to the material delivery opening of the furnace, and means to actuate said holder support to elevate the holder.

3. In apparatus for heating material in coils, a furnace chamber having a material delivery opening, a coil holder movable in the chamber, and means operable when the holder is in a predetermined position with respect to said delivery opening to permit the holder to rotate for the withdrawal of a coil therefrom by unwinding.

4. In apparatus for heating material in coils, a furnace chamber having a material delivery opening, a coil holder movable in the chamber, and a vertical spindle extending into the chamber and adapted to be engageable with the holder to rotatably support the same.

5. In apparatus for heating material in coils, a furnace chamber having a material delivery opening, a track in the chamber, a coil holder movable on said track, and a vertical spindle beneath the track and adapted to be engageable with the holder to rotatably support the same.

6. In apparatus for heating material in coils, a furnace chamber having a material delivery opening, a track in the chamber, a coil holder movable on said track, a vertical spindle beneath the track adapted to be engageable with the holder to rotatably support the same, and means for actuating the spindle to elevate the holder out of engagement with the track.

7. In apparatus of the class described, a coil holder comprising a hub having a recess in the lower face thereof for the reception of a spindle, coil supporting arms carried by

said hub and having their outer ends rearwardly curved, and retainers on said holder adapted to overlie a coil thereon, said retainers being pivotally supported to be movable out of the path of application of a coil to the holder.

8. In apparatus of the class described, a coil holder comprising a hub having a recess in the lower face thereof for the reception of 10 a spindle, coil supporting arms carried by said hub, and pivoted retainers on said holder adapted to overlie a coil thereon, the ends of the hub arms and of the retainers being

rearwardly curved and the lower part of said hub being provided with a guide projection. 15

9. In apparatus of the class described, a coil holder comprising a hub and coil supporting arms carried thereby and having their ends rearwardly curved, and pivoted 20 retaining members carried by the holder and adapted to overlie a coil thereon, the ends of said members being rearwardly curved.

In testimony whereof, I hereunto affix my signature this 18 day of December, 1926.

EDWARD J. MILLER.
